UNITED STATES PATENT OFFICE.

RUPERT A. EMMONS, OF WASHINGTON, DISTRICT OF COLUMBIA.

FLYING-MACHINE.

1,264,037.

Specification of Letters Patent. Patented Apr. 23, 1918.

Application filed April 5, 1916. Serial No. 39,091.

To all whom it may concern:

Be it known that I, RUPERT A. EMMONS, a citizen of the United States, residing at Washington, in the District of Columbia, 5 have invented certain new and useful Improvements in Flying-Machines, of which the following is a specification.

My invention relates to improvements in flying machines, and one object of my invention is the provision of a machine which will be under perfect control of the aviator under all conditions and which will respond instantly when necessary to rise or land and be guided with ease and certainty.

15 Another object of my invention is the provision of a flying machine the planes of which will be carried by the body in such a manner as to receive all lateral and longitudinal air thrusts or currents and so direct 20 these thrusts of the air upon the planes as to stabilize the craft and cause it to travel in the proper direction.

Another object of my invention is the provision of a flying machine which will 25 present a wide spread of wing surface to insure the full trapping of the air and which will accommodate the longitudinal and lateral thrusts of wind to cause the machine to right itself under varying conditions and 30 attain complete and perfect stability.

Another object of my invention is the production of a flying machine which will have 35 a large wing area in a compact, small space; which can be controlled with ease and certainty; which will stabilize under all conditions of wind direction and which will be durable and inexpensive of production to provide an efficient and practical machine.

With these and other objects in view the 40 invention consists of a flying machine embodying a novel construction and arrangement of the planes with reference to the body, propelling and guiding mechanism, to produce the results required in a practical 45 and efficient manner.

The invention further consists of a flying machine embodying novel features of construction and combination of parts, substantially as shown, described and claimed 50 herein, it being understood that any changes may be made in the construction, which come within the spirit or scope of my invention.

In the drawings:—

55 Figure 1 represents a top plan view of the

preferred construction of my flying machine.

Fig. 2 represents a front view thereof.

Fig. 3 represents a side elevation of the preferred form of machine.

Fig. 4 represents a front view of a modified construction of machine, embodying 60 multiple or triplanes.

Fig. 5 represents a top plan view of a further modified construction, embodying 65 multiple or triplanes.

Fig. 6 represents a front elevation of this multiple or triplane construction of machine.

Fig. 7 represents a top plan view of a further modified form of biplane machine, and

Fig. 8 represents a side view of said construction.

Fig. 9 represents a side view of a machine having a slight change or modification, and 75

Fig. 10 represents a top plan view of a modified construction of machine.

Referring by numeral to the drawings, in which similar characters denote the same parts in all the views:—

The numeral 1, designates the body, fuselage or nacelle of the machine which may be of any preferred construction, and provided or equipped with any suitable type of launching, steering and landing means.

80 The machine may be of the biplane type as illustrated in Figs. 1, 2, 3, 7, 8, 9 and 10, or of the triplane or other multiplane construction as disclosed in Figs. 4, 5 and 6, in all cases the broad general features of my invention being embodied.

85 The body 1, carries in Figs. 1, 2, 3, 7, 8, 9 and 10, a supporting surface of the biplane type, comprising an upper set of wings 2, and a lower set of wings 3, the upper and lower wings being supported above and below the body, by the suitable bracing and connecting means or structure 4.

90 The planes are concaved or cambered and the upper plane has its wings extending upwardly and forwardly, while the lower plane has its wings extending downwardly and rearwardly with reference to the body and at the proper dihedral angle.

95 In the construction of my machine shown in Fig. 10, the planes are arranged at different levels and to the fore and aft of each other, the upper plane having its wings 5, supported at their inner meeting ends 6, near the tail of the machine and extending 100

upwardly and forwardly, while the wings 7, of the lower plane, have their meeting ends 8, adjacent the propelling mechanism and forward part of the body and extend downwardly and rearwardly with reference to the body and upper planes.

In the form of my machine described and shown in Figs. 1, 2, 3, 7, 8, 9 and 10, two planes are employed and the same construction, particularly with reference to the use of the planes is in evidence, this type giving a very large wing area and receiving the lateral and longitudinal thrust of air to cause the machine to travel properly and to stabilize under the varying conditions.

Fig. 4 represents a construction having triplanes arranged above each other, and with the outer sections 14 of the lowest plane angled upwardly and raked to the front, and 20 with the outer sections 15 of the upper plane angled downwardly and raked to the rear.

In the construction shown in Figs. 5 and 6, the same arrangement and construction of upper and lower wings 9 and 10, is employed, as shown in Fig. 1, with the addition of a horizontal plane 11, arranged between said wings 9 and 10, this producing a triplane type of machine.

In Figs. 7 and 8, I employ an upper plane 30 12, disposed transversely, whose wings extend upwardly with reference to the body, and a lower plane 13 whose wings extend downwardly and rearwardly with reference to the body and at the proper dihedral angle.

35 In the form of my invention shown in Fig. 3, the biplane type is used to illustrate the effect of the air upon the wings, for the purpose of demonstrating the operation and advantages of my machine over other aircraft.

40 In this figure, the point *a* represents the center of gravity of the machine, point *b*, represents the center of pressure of the air against the upper wing due to the forward movement of the machine, point *c* represents 45 this center of pressure on the lower wing. The line A—A represents the line of thrust of the propeller. The line of thrust A—A runs through the center of gravity *a*. This is not absolutely necessary, but such construction

50 is used here as it more simply illustrates the principles whereby longitudinal stability is secured. Now when the machine is traveling forward these wings act as a lever with its fulcrum at *a*, and with equal leverages *a b* and *a c* when the machine is traveling in a 55 normal horizontal course or line of flight.

Now if the machine leaves the horizontal line of flight and starts climbing, say at an angle of 30 degrees the centers of pressure on 60 the planes will move to the points *b'* and *c'* in which case the leverages of the two wings are no longer equal, but the leverage of the lower wing *c' d* is greater than the leverage of the upper wing *b' d*, and this greater leverage of the lower wing would bring the ma-

chine back to its normal horizontal line of flight unless prevented by the operation of the tail steering mechanism.

Lateral stability is secured in the following manner:—Considering first the lower lifting plane, the wings of which are angled downwardly and rearwardly. When tipped laterally the pressure of the air against the wing on the lower side is much greater than against the wing on the higher side, due to 70 the fact that the angle of incidence of the wing on the lower side increases in tipping and decreasing with the wing on the higher side, and also to the fact that the machine tends to fall toward the lower side and so increasing the air pressure against the wing on the lower side. With the upper plane, when the machine is tipped laterally, the pressure of the air against the wing on the lower side increases and decreases against the wing on 75 the upper side, this being due to the tendency of the machine to fall toward the lower side.

Another advantage of my machine is illustrated in Fig. 2, the arrows *m* and *m'* representing a lateral gust of wind, which, striking against the upper and lower planes produce two counteracting turning forces represented by arrows *n* and *n'*, which forces, being equal would not in any way tend to tip or 80 rock the machine. So that with the use of these dihedrally angled planes all tendency for the machine to rock and become unmanageable is eliminated.

It will also be readily understood that it 100 makes no difference which of the two supporting planes is on top or which is the bottom plane. The principle is the same as long as the wings of one plane are angled downwardly and rearwardly and the wings 105 of the other plane are angled upwardly and forwardly.

In the form of my invention shown in Fig. 9 the planes are arranged at a different height or level with reference to the body, 110 but the effect or action is exactly the same as in the other constructions.

I claim:—

1. A flying machine having supporting planes so arranged that during one or more 115 longitudinal angulations of the machine with respect to its line of flight, the wings of one or more planes will present to this line of flight a negative dihedral, and the wings of one or more other planes will present to 120 this line of flight a positive dihedral, and the wings of these planes will be so arranged that those presenting a negative dihedral to the line of flight will be raked outwardly and rearwardly, and those presenting a positive dihedral to the line of flight will be raked outwardly and forwardly.

2. A flying machine provided with supporting planes, the wings of certain of these planes being dihedrally angled downwardly 130

and raked to the rear, and the wings of other of these planes being dihedrally angled upwardly and raked to the front.

3. A flying machine provided with supporting planes, the wings of certain of these planes being dihedrally angled downwardly and raked to the rear, and the wings of other of these planes being dihedrally angled upwardly and raked to the front, the dihedrally angled wings being of such arrangement and area that lateral currents of air will produce against them equal counter-acting forces.

4. A flying machine with supporting planes, each plane comprising dihedrally arranged wings, the wings of one plane being negatively dihedrally angled and raked to the rear, and the wings of the other plane being positively dihedrally angled and raked to the front.

5. A flying machine with supporting planes, of which one or more wings are dihedrally angled downwardly and raked to the rear, and of which one or more wings are dihedrally angled upwardly and raked to the front.

6. A flying machine consisting of superposed planes, the wings of one plane being angled downwardly and rearwardly, and the wings of the other plane being angled upwardly and forwardly, and with a pair of wings disposed between the superposed wings.

7. A flying machine having supporting planes, with the wings of one or more planes or sections of wings angled downwardly and rearwardly, and the wings or sections of wings of one or more planes angled upwardly and forwardly.

8. A flying machine embodying two lift-

ing planes, the wings of one plane being positively dihedrally angled and the wings of the other plane being negatively dihedrally angled and raked to the rear.

9. A flying machine with supporting planes arranged one in advance of the other of which the wings of one or more planes are negatively dihedrally angled and raked to the rear, and of which the wings of one or more planes are positively dihedrally angled and raked to the front.

10. A flying machine with supporting planes, of which certain wings or sections of planes are negatively dihedrally angled and raked to the rear, and of which certain other wings or sections of planes are positively dihedrally angled and raked to the front.

11. A flying machine having a supporting surface comprising wings of which certain wings are dihedrally angled in an outward and upward and forward direction, and of which certain other wings are dihedrally angled in an outward and downward and rearward direction.

12. A flying machine having a supporting surface of which certain wings or lifting planes or sections of lifting planes are dihedrally angled in an outward and upward and forward direction, and of which certain other wings or lifting planes or sections of lifting planes are dihedrally angled in an outward and downward and rearward direction.

In testimony whereof I affix my signature in the presence of two witnesses.
